ARTHUR NUTT, OF KENMORE, NEW YORK, ASSIGNOR TO CURTISS AEROPLANE & MOTOR COMPANY, INC., A CORPORATION OF NEW YORK.

VALVE-OPERATING MECHANISM.

Application filed February 14, 1927. Serial No. 168,206.

My invention relates to internal combustion motors and is more particularly concerned with the valve operating mechanism thereof.

Many types of racing motors, as well as a large number of aeronautical motors, are characterized by the provision of two or more intake valves and two or more exhaust valves per motor cylinder, such multiple valve equipment being conducive to a greater motor efficiency and a more rapid and better distribution of both the incoming and the spent fuel or gas. In using a multiple number of valves per motor cylinder, it has been the practice heretofore to either cross-port one intake and one exhaust valve of each pair of valves and use a single cam shaft, or its equivalent, or, where cross-porting is avoided, to use two cam shafts for each bloc or bank of cylinders. Regardless of the construction employed the weight and complexity of the valve operating mechanism is excessive.

The particular object of the present invention is to so organize the valve operating mechanism of a multi-cylinder internal combustion motor having two or more intake and two or more exhaust valves per motor cylinder as to avoid the necessity of cross-porting the valves and yet, in the preferred embodiment of the invention, provide for the proper operation thereof thru the use of a single cam shaft. Instead of arranging the intake and exhaust valves alternately at opposite sides of the plane of the cylinder axes and extending valve tappets crosswise the cylinder bank, all of the intake valves are arranged at one side of said plane and all of the exhaust valves are arranged at the opposite side thereof. This arrangement coupled with the fact that the valve tappets of the corresponding valves of each motor cylinder extend lengthwise the motor and are offset laterally, enables me to use, with excellent results, a single cam shaft or its equivalent, said shaft being preferably extended longitudinally of the motor in the plane of the cylinder axes. Thus organized, the construction of the valve operating mechanism is much simplified and the weight of the motor, considered in its entirety, many pounds reduced, e. g., a consideration of vast importance in the design and construction of motors for use in aircraft.

A further object of the invention is to so

form the laterally offset head portions of the valve tappets as to admit of the interchangeability thereof; such interchangeability resulting from a head formation in which the arms of the head portions of the valve tappets are of unequal length as measured, in each instance, from the offset.

A still further object of the invention is to reduce the projected area of an internal combustion motor, and especially an aeronautical internal combustion motor, by interpolating in the driving connection for the overhead cam shaft suitable gearing so disposed in its relation to the axis of the cam shaft as to avoid the necessity of mounting at the end thereof a relatively large bevel gear.

Other objects, advantages and improved results will be hereinafter pointed out.

In the drawings, wherein like reference characters denote like or corresponding parts,

Fig. 1 is a plan view of one of the cylinders of a multi-cylinder internal combustion motor having four valves per cylinder, and in which a single cam shaft is provided for the proper operation of the total number of valves;

Fig. 2 is a side elevation of the structure illustrated in Fig. 1;

Fig. 3 is a vertical sectional view;

Fig. 4 is a diagrammatic illustration of a bank of engine cylinders showing the relation of the multiple valve tappets and the single operating cam shaft;

Fig. 5 is a perspective view of one of the valve tappets;

Fig. 6 is a view similar to Fig. 2 illustrating a modified cam shaft drive;

Fig. 7 is a vertical sectional view of the structure illustrated in Fig. 6;

Fig. 8 is a plan view of a further modification;

Fig. 9 is a longitudinal vertical sectional view of the modification of Fig. 8; and

Fig. 10 is a transverse sectional view of the structure illustrated in Fig. 9.

In the embodiment of the invention selected for illustration (see Fig. 4) six engine cylinders are provided. Any number of engine cylinders may, however, be used or, if desired, even a single cylinder may be employed, altho the invention is especially designed for use in aeronautical motors wherein a plural number of cylinders are provided, said cylinders being preferably in line whether

- or not one, two or more banks of cylinders are provided. The engine cylinders are designated as 10. Each cylinder is provided with two intake valves 11 and two exhaust valves 12, the valve stems of each being carried thru the cylinder head casting to project thereabove or therebeyond as shown. For each corresponding pair of valves a single valve tappet is provided, the valve tappets for the intake valves 11 being designated as 14 and the valve tappets for the exhaust valves 12 being designated as 13. Said valve tappets 13 and 14, or rather the head portions thereof, extend longitudinally of the motor or cylinder bank in connection with which they are used, the head portions of the intake valve tappets 14 being preferably disposed in longitudinal alignment at one side of the plane of the cylinder axes and the head portions of the exhaust valve tappets 13 being similarly disposed at the opposite side thereof. Such a valve tappet arrangement is advantageous in that the necessity for cross-porting is avoided. Heretofore, in so far as I am aware, where four valves per cylinder have been provided, it has been the customary practice to alternately arrange the intake and the exhaust valves at opposite sides of the plane of the cylinder axes, such an arrangement necessitating that one port for each pair of valves be extended beyond and across the plane of the cylinder axes to the end that all intake valve ports may terminate at one side of the bank of cylinders and all exhaust valve ports at the opposite side thereof. By disposing the valves of the motor as herein illustrated, this objectionable cross-porting feature is overcome.
- Not only is cross-porting avoided as previously mentioned, but in the present invention, thru an improved tappet construction, a single operating cam shaft 15 or its equivalent is made to function as the means of operating the total number of valves. The valve tappets 13 and 14 are of identical construction. Each includes a stem or shank portion 16, an offset portion 17, and a head portion 18, the latter being formed at the end of the offset to span or bridge the distance between corresponding valves. The arms of the head portion (see Fig. 5) are of unequal length as measured from the offset, to the end that the valve tappets 13 and 14 may be interchangeable. Such interchangeability is especially desirable as a service feature in that it admits of the use of a single type of valve tappet as a replacement part whether intended for use in connection with the exhaust valves or the intake valves of the motor.
- Said valve tappets, as intimated, are of the T-type. The shank portions thereof engage in guides 19 fastened to the cylinder heads, whereas the head portions 18, instead of extending crosswise the motor, as heretofore, extend lengthwise thereof in the manner indicat-

ed. Thus organized, a single cam shaft, or its equivalent, if extended longitudinally of the cylinder bank as shown, is made to function as the operating means for the total number of valves. The cams 20 of the cam shaft act directly upon enlargements 21' formed on the valve tappets directly above the shank portions 16 thereof, such direct action being conducive to a proper operation of the valves without incurring any side thrust whatsoever. Valve springs 21, encircling the valve stems and engaging in depressions 22 formed in the cylinder head, seat the valves automatically.

To operate the cam shaft, it is the usual practice to provide at one end thereof a relatively large bevel gear, such gear (see Figs. 6 and 7) being usually mounted directly upon the cam shaft. A gear thus mounted, especially in aeronautical motors, is found to be objectionable because of the increased area which it offers in flight. To reduce the projected area of the motor, such gear, designated as 22', is dropped down to an extent best illustrated in Figs. 2 and 3, wherein it will be observed that the gear lies wholly within the plane of the forward bearing 23 provided for the cam shaft 15. Said bearing 23, beneath the cam shaft 15, also supports a stub shaft 24 upon which a spur gear 25 is mounted. Said gear 25 is in mesh with a similar gear 26 mounted on the cam shaft. Preferably the bevel gear 22' and the spur gear 25 are in line, the former (see Fig. 2) being driven thru a bevel pinion 26' mounted on a drive shaft 27 geared to the crank shaft of the motor and driven therefrom by any suitable means.

In the modification of Figs. 6 and 7 the valve arrangement and the valve operating mechanism are the same as previously described. The intermediate gear 25 of the cam shaft, however, is omitted. In said Figs. 6 and 7 the driving pinion for the cam shaft gear engages the bevel gear, said last mentioned gear being directly mounted upon the cam shaft. Thus organized, a slight reduction in weight is obtained altho the projected area of the motor remains the same.

In the modification of Figs. 8 to 10, inclusive, a geared down drive is obtained thru the use of an intermediate gear 30, which gear 30 is in mesh with two spur gears 31 mounted respectively upon the ends of two cam shafts 32. In this modification, altho the projected area of the motor is reduced, it is necessary, for the proper operation of the valves, that two cam shafts be provided for each bank or bloc of cylinders.

While I have described my invention in detail in its present preferred embodiment, it will be obvious to those skilled in the art after understanding my invention, that various changes and modifications may be made therein without departing from the spirit or

scope thereof. I aim in the appended claims to cover all such modifications and changes.

What I claim is:

1. In valve operating mechanism for internal combustion motors, a pair of intake valves and a pair of exhaust valves for each motor cylinder, said intake valves being disposed at one side of a plane passing thru the axes of the motor cylinders and said exhaust valves being disposed at the opposite side of said plane, a reciprocating valve tappet for each pair of valves, and devices movable about an axis common to the total number thereof to actuate said tappets. 75
2. In valve operating mechanism for internal combustion motors, a pair of intake valves and a pair of exhaust valves for each motor cylinder, said intake valves being disposed at one side of a plane passing thru the axes of the motor cylinders and said exhaust valves being disposed at the opposite side of said plane, a valve tappet for each pair of valves, each valve tappet including a reciprocating stem portion and a laterally offset head portion rigid in its relation to said stem portion, said head portions being likewise disposed respectively at opposite sides of said plane, and means operable to actuate said tappets. 80
3. In valve operating mechanism for internal combustion motors, a pair of intake valves and a pair of exhaust valves for each motor cylinder, the total number of intake valves being disposed overhead and at one side of a plane passing thru the axes of the motor cylinders and the total number of exhaust valves being disposed overhead and on the opposite side of said plane, reciprocating substantially T-shaped valve tappets common to the corresponding valves of each cylinder, and mechanism operable to actuate said tappets. 85
4. In valve operating mechanism for internal combustion motors, a pair of intake valves and a pair of exhaust valves for each motor cylinder, said intake valves being disposed at the outer cylinder ends and on one side of a plane passing thru the axes of the motor cylinders and said exhaust valves being disposed at the outer cylinder ends and on the opposite side of said plane, an overhead valve tappet for each pair of valves, each valve tappet including a stem portion, and a laterally offset head portion, said head portions being likewise disposed respectively at opposite sides of said plane and being extended in each instance parallel thereto, and overhead cam shaft operable to actuate said tappets. 90
5. In valve operating mechanism for internal combustion motors, a pair of intake valves and a pair of exhaust valves for each motor cylinder, said intake valves being disposed at one side of a plane passing thru the axes of the motor cylinders and said exhaust valves being disposed at the opposite side of said plane, a valve tappet for each pair of valves, each valve tappet including a stem portion and a laterally offset head portion, said stem portions being aligned in a plane common to the total number thereof and said head portions being aligned in groups disposed respectively at opposite sides of said plane, and means operable to actuate said tappets. 95
6. In valve operating mechanism for internal combustion motors, a pair of intake valves and a pair of exhaust valves for each motor cylinder, said intake valves being disposed at one side of a plane passing thru the axes of the motor cylinders and said exhaust valves being disposed at the opposite side of said plane, a valve tappet for each pair of valves, each valve tappet including a stem portion and a laterally offset head portion, said stem portions being aligned in a plane common to the total number thereof and said head portions being aligned in groups disposed respectively at opposite sides of said plane, and devices for actuating said tappets movable about an axis common to the total number thereof and engaging said tappets in the plane of the valve tappet stems. 100
7. Valve operating mechanism for internal combustion motors including a pair of T-tappets for each motor cylinder, each T-tappet having its head portion laterally offset with respect to its stem, and said head portions, with respect to each other, being oppositely laterally offset and being disposed respectively at opposite sides of a plane passing thru the axis of said cylinder, and means disposed in the plane of said axis for actuating the respective tappets. 105
8. Valve operating mechanism for multi-cylinder internal combustion motors including a pair of T-tappets for each motor cylinder, each tappet having its head portion offset laterally with respect to its stem, said stem portions, in each instance, being aligned and said head portions being oppositely offset to lie respectively at opposite sides of a plane passing thru the axes of said cylinders, and mechanism operable to actuate said tappets. 110
9. Valve operating mechanism for internal combustion motors including a pair of valve tappets having oppositely laterally offset head portions disposed respectively at opposite sides of a plane passing thru the axis of said cylinder, said tappets being interchangeable, and mechanism operable to actuate said tappets. 115
10. Valve operating mechanism for multi-cylinder internal combustion motors including a pair of T-tappets for each motor cylinder, each T-tappet having its head portion offset laterally with respect to its stem, said head portions being disposed respectively at opposite sides of a plane passing thru the 120
11. Valve operating mechanism for multi-cylinder internal combustion motors including a pair of valve tappets having oppositely laterally offset head portions disposed respectively at opposite sides of a plane passing thru the axis of said cylinder, said tappets being interchangeable, and mechanism operable to actuate said tappets. 125
12. Valve operating mechanism for multi-cylinder internal combustion motors including a pair of valve tappets having oppositely laterally offset head portions disposed respectively at opposite sides of a plane passing thru the 130

axes of said cylinders, guides for the valve tappet stems, and a single cam shaft operable to actuate the total number of valve tappets, said cam shaft being disposed in said above 5 mentioned plane.

11. Valve operating mechanism for multi-cylinder internal combustion motors including two or more intake valves and two or more exhaust valves for each motor cylinder, 10 said intake valves being disposed at one side of a plane passing thru the axes of said cylinders and said exhaust valves being disposed on the opposite side of said plane, a pair of T-tappets for each cylinder, each T-tappet 15 having its head portion offset laterally with respect to its stem, and said head portions

being disposed respectively on opposite sides of said plane whereby a single valve tappet is adapted to actuate a pair of valves, and an operating means so related to the total number of valve tappets as to engage the offset portions thereof in the plane of the valve tappet stems. 20

12. A T-tappet for internal combustion motors comprising a stem portion and a head portion, said head portion, as measured from said stem portion, including a long arm and a short arm respectively. 25

In testimony whereof I hereunto affix my signature.

ARTHUR NUTT.
